UNITED STATES PATENT OFFICE

CLARENCE E. LOMAX, OF OAK PARK, ILLINOIS, ASSIGNOR TO RESERVE HOLDING COMPANY, OF KANSAS CITY, MISSOURI, A CORPORATION OF DELAWARE

TELEPHONE SYSTEM

Application filed March 12, 1927. Serial No. 174,734.

This invention relates to telephone systems in general, but more particularly to toll switching systems in which all toll connections within a certain area are established and 5 supervised from a main toll board.

In telephone systems extending over an area including several more or less widely scattered communities or exchanges, inter-connected by toll or long distance lines, the practice of completing and supervising all connections between the exchanges of the different communities, as well as all connections to outside points, from the main toll board located in one of the exchanges is often advantageously followed. An obvious advantage gained by this practice is that it obviates the necessity of employing a toll operator at each of the separate exchanges. Furthermore, the clerical work concerning the charges for toll connections is concentrated at one central office. In 10 large telephone systems of this kind for well known economical reasons each exchange is not connected directly with every other exchange in the system, but is usually connected 15 only with one or two of the nearest exchanges. For this reason special consideration must be given to the methods employed in carrying out the above practice in order that it may be done in the most economical manner, both in regard 20 to the amount of equipment needed and in regard to the trunks used.

The main object of this invention consists in the provision of improved circuits for use in a telephone system as described above where- 25 by the toll operator may be called from any one of the exchanges over one of the trunks extending to the exchange in which the toll board is located and whereby the toll operator may then control the establishment of the de- 30 sired connection over the most direct route and maintain supervision thereof over that same trunk line.

The object of the invention and the various features thereof, will be described in detail 35 in the following specifications with the aid of the accompanying drawings which illustrate by means of the usual schematic circuit diagrams and trunking diagrams a section of a telephone system embodying the principles of 40 the invention. It is understood of course that

the invention is in no way limited to any particular system, the one shown in part in the drawings having been chosen merely for illustration.

The drawings to be most easily understood 55 should be placed with Fig. 2 to the right of Fig. 1, and with the corresponding lines in alignment. The apparatus shown between the dotted vertical line in Fig. 1 and the dotted vertical line in Fig. 2 is located in one ex- 60 change, which will be referred to as exchange A. The exchange A is an automatic exchange serving the subscribers of one community, and calls within this community are all established automatically without the aid of an operator. 65 The switches for setting up these local connections have been shown diagrammatically. For example, the local subscriber's substation A' terminates in the individual line switch LS, which has access together with other similar 70 lineswitches to the local selectors, such as selector S. In the banks of the local selectors, access is had to one or more groups of connectors, each group being accessible in a sepa- 75 rate level. Each group of connectors has ac- 80 cess to a separate group of subscribers' lines. The connector C shown is one of the group having access to the group of subscribers' lines including the line to substations A'.

Exchange A is connected with the exchange 80 of another community (which will be referred to as exchange B) by one or more toll trunk lines, such as the one comprising conductors 252 and 253. At this latter exchange, the main toll board is located from which all toll 85 connections for the system are completed. In the exchange A, at the trunk relay group TRG, this trunk line is divided into two branches. The outgoing branch, that is, the branch over which connections to the toll board are extended, comprises conductors 22, 23, 24, and together with the corresponding branches of the other trunks to the exchange B is accessible in a particular level in the 90 banks of the local selectors. The incoming branch, that is, the branch over which the toll operator sets up toll connections, comprises conductors 22', 23' and 24' and terminates in the incoming selector S'. The corresponding 95 100

branches of the other trunks likewise terminate in similar incoming selectors.

Exchange A is also connected with the exchange of another community (which will be referred to as exchange C) by one or more toll trunk lines, such as the one comprising conductors 2 and 3. This trunk line terminates at exchange A in the line switch LS' by way of the impulse repeater R, and is accessible with the other similar trunks from exchange C in a particular level in the banks of the incoming selectors, such as selector S'. In the banks of the line switch LS' access is also had to the outgoing branches of the trunk lines extending to exchange B.

In a small community near the community served by the exchange A, a manual paystation is located. The line from this paystation terminates at the exchange A in the line switch LS² via the ringing trunk circuit RTC, and is also accessible in the first set of contacts in a particular level in the banks of the incoming selectors. The test contacts of the other sets in this same level are multiply connected to ground. In the bank of the line switch LS² access is also had to the outgoing branches of the trunk lines extending to the exchange B, its banks being multiplied with the banks of the line switches such as line switch LS'.

Those levels of banks of the local selectors in which access is had to various groups of connectors are multiplied with the corresponding levels of the incoming selectors, so that the local selectors and incoming selectors have common access to the connectors for completing local connections. The other levels are not multiplied between the two kinds of selectors.

The line switches LS, LS', and LS² in the exchange A may be of any suitable type, such as the well known rotary type. The selectors, both the local selectors and the incoming selectors, and the connectors may be, for example, of the well known Strowger vertical and rotary type. The repeater R may be like the two-way repeater shown and described in detail in the John Wicks Patent No. 1,643,797, granted Sept. 27, 1927. The trunk relay group TRG forms a particular part of this invention and will be described in detail subsequently. The ringing trunk circuit RTC will also be described in detail in the following descriptions.

At the exchange B, the trunk lines from the exchange A terminate at the main toll board in jacks, such as jack J. Individual to each trunk is a call lamp, such as the lamp L, a disconnect lamp, such as the lamp L', a dialling key, such as key K, for associating the dial D with the trunk, and a group of relays for controlling the signalling, the dialling, and the supervisory circuits. The operator is also provided with cord circuits (not shown) which may be of any suitable

type having ground potential connected to the sleeve conductor. The trunk lines extending between exchanges A and B are composed in the usual way by means of toroidal compositing coils, shown conventionally, to provide a dialling circuit over one wire of the trunk line, and also another circuit over the other wire that may be used for telegraphy or as a dialling circuit for another trunk line.

The exchange C is also assumed to be an automatic exchange, with suitable switches for completing local connections. It is also assumed that the trunk lines such as the one comprising conductors 2 and 3 terminate thereat in incoming selectors, and are accessible in the banks of local seletcors via repeaters in the well known manner.

With the general object of the invention, the layout of the system, and the apparatus as shown, in mind, a further understanding and appreciation of the invention may be gained from a detailed description of the operation thereof. To describe the operation, it will first be assumed that a subscriber served by the exchange C wishes to be connected with the manual pay station P.

To obtain this connection, the calling subscriber at the exchange C removes his receiver and dials the toll or long distance number, which causes automatic switches in the exchange C to connect with and extend the connection over one of the trunk lines extending to exchange A, such as, for example, the one comprising conductors 2 and 3. The extension of the connection to the exchange A over this trunk line causes the lineswitch LS' to operate in the usual manner to select an idle trunk accessible in its banks. It may be assumed that the trunk selected by the lineswitch LS' is the one comprising conductors 22, 23, and 24. In selecting this trunk, lineswitch LS' extends the connection to the trunk relay group TRG and also connects ground potential to release conductor 24 and to release conductor 34 via conductor 14 thereby marking this trunk line engaged to all switches having access thereto.

By the extension of the connection to the trunk relay group TRG, a circuit is closed for line relay 204 including the two trunk conductor in series. Relay 204, in operating, closes the circuits for release relay 203 and an auxiliary relay 202 at armature 213, and also prepares a circuit for control relay 201 at armature 212. Release relay 203 energizes and at armature 210 connects ground to release conductor 24 to maintain the lineswitch LS' operated and maintain the trunk in question marked engaged. At armature 209 a point in the talking circuit is closed, and at armature 211 ground potential, which is normally connected to conductor 255 by way of armature 228 and its resting contact and the winding of impulsing relay 221, is discon-

5 nected therefrom and battery through re-
sistance 205 is substituted therefor. Relay
202 is equipped with a vibrating armature,
conventionally shown in Fig. 2. When relay
202 is energized as a result of the operation
of relay 204, it starts the vibration of its
vibrating armature 208 which in each for-
ward motion momentarily closes the circuit
of control relay 201. However, due to its
10 impedance, relay 201 does not become suffi-
ciently energized at each momentary ener-
gization to operate its armatures, and only
after the elapse of an appreciable interval
does armature 208 come to rest in engage-
15 ment with its working contact and maintain
the circuit of relay 201 closed. During this
interval battery potential is connected to con-
ductor 255 and a closed circuit may be traced
which extends from battery through resist-
20 ance 205, resting contact and armature 206,
working contact and armature 211, conduc-
tor 255, through the upper right hand coil
T², over the upper trunk conductor 252 to
the main toll board at exchange B, and there-
25 through the upper left hand coil T¹¹, con-
ductor 257, armature 272 and the resting con-
tact, through the lower winding of signalling
relay 265 to ground. Relay 265 energizes and
closes a locking circuit for its upper winding
30 in series with the call lamp L at armature
273. The lamp L is lighted and notifies the
operator of the incoming call.

After the lapse of the aforesaid interval,
relay 201 is continuously energized and there-
35 fore operates and prepares a circuit for relay
224 at armature 207, and at armature 206
again connects ground potential in series with
impulsing relay 221 to conductor 255, dis-
connecting battery through resistance 205
40 therefrom. Thus it is seen that relays 201,
202, and 203 have functioned to substitute
battery potential for the ground potential
on conductor 255 for a short time in order
to cause the lighting of lamp L by ener-
45 gizing relay 265. The reapplication of
ground potential to conductor 255 recondi-
tions the circuits for dialling as will be de-
scribed presently.

To answer the call, the toll operator at the
50 toll board inserts the answering plug of an
idle cord circuit into the jack J. A circuit is
thereby closed for sleeve relay 264 from
ground by way of the sleeve of the plug of the
cord circuit used, sleeve of jack J, holding
55 conductor 277, through the winding of relay
264 to battery. Relay 264 operates and at
armature 271 opens the circuit of the upper
winding of relay 265 and the lamp L thereby
causing relay 265 to deenergize and the lamp
60 L to be extinguished. At armature 272 a cir-
cuit is prepared for dialing and later for giv-
ing the disconnect signal, to be described
later.

After inserting the plug of a cord in the
65 jack J, the operator will throw her listening

key and inquire the wants of the calling sub-
scriber. After receiving this information
including the name or the number of the
wanted subscriber, the toll operator operates
the key K. As a result, the dial-control re-
70 lay 262 is operated over the circuit including
springs 274. Relay 262, in operating, closes
a locking circuit for itself at armature 268
and the working contact to the holding con-
ductor 277, and at armature 269 completes the
75 dialing circuit, springs 275 of key K now be-
ing closed, for controlling the setting up of
the desired connection. This circuit may be
traced from battery in series with dial D,
springs 275, working contact and armature
80 269, working contact and armature 272, con-
ductor 257, through the upper left hand coil
T¹¹, trunk conductor 252, through the upper
right hand coil T², conductor 255, armature
211 and working contact, armature 206 and
85 the working contact, through the winding of
impulsing relay 221, resting contact and
armature 228 to ground. Impulsing relay 221
thereupon operates and closes a point in the
90 talking circuit to be described later at arma-
ture 226, and at armature 227 closes a bridge
across the trunk conductors 22' and 23', which
includes the left hand windings of repeating
coil R³ and the upper winding of the polar-
ized relay 223. It should be noted that the
95 lower polarizing winding of relay 223 is en-
ergized from ground on conductor 24. The
placing of a bridge across the conductor 22'
and 23' closes the circuit for the line relay in
the selector S' thereby causing the selector S
100 to prepare itself for operation in the well
known manner. The current flow in the up-
per winding of the polarized relay 223 at the
time is in such a direction that this relay does
not now operate.

The toll operator now dials the number
of the paystation P, after which she again
restores the key K to normal. As a result,
springs 276 are closed and battery through
the winding of the supervisory relay 263
110 is substituted for the battery in series with the
dial D. This causes relay 263 to operate and
close a circuit for the supervisory lamp L'
at armature 270, causing the lighting of the
lamp L'.

In this example, the number of the pay-
station P comprises only one digit. Respon-
sive to the dialing thereof by the toll operator,
the selector S' raises its wipers opposite the
level corresponding to the digit dialled, and
then rotates its wipers into engagement with
the first set of bank contacts in this level.

If the paystation is busy at this time,
ground potential will be encountered by
the test wiper of the selector S', which will
cause the selector S' to step to the next set
of bank contacts. Since all the remaining
sets have been artificially marked busy, the
selector S' will be stepped past the last
set of contacts and give the operator the busy
125

signal, in the well known manner. It should be noted that connections to or for the paystation P can only be completed from the main toll board, so if there is only one operator there, she will know beforehand whether the paystation P is busy or idle, and if busy, will notify the calling subscriber accordingly as soon as she learns that such connection is desired.

It is assumed, however, that the paystation P is idle at this time. Then no ground potential will be present on the release conductor 44, and the selector S' will operate to extend the connection to the ringing trunk circuit RTC. As a result, ground potential is connected to release conductor 44 and 18 serially connected with conductors 24 and 24', thereby causing the cut-off line relay in the line-switch LS² to disconnect the normal ground and battery connections from the paystation line. In extending the connection to the ringing trunk circuit RTC, the circuit for relay 54 is also completed, this circuit including the bridge at the trunk relay group TRG across conductors 22' and 23', now connected with conductors 42 and 43, respectively. Relay 54 operates and closes the circuit of relay 51. Relay 51 operates and grounds conductor 44 at armature 56 so that the apparatus in exchange A associated with the connection may be maintained busy after the called party answers until the operator releases the connection, as will be further described in later descriptions. At armatures 55 and 57, the ringing circuit to signal the party at the paystation is closed, this circuit extending from conductor 62, to which the grounded ringing generator G and direct ground are alternately connected, resting contact and armature 60 working contact and armature 57, line conductor 7, through the ringer at the paystation P, line conductor 6, armature 55 and its working contact, armature 58 and its resting contact, through the upper winding of ring-cut-off relay 52 to battery. The ringer at the paystation is thus operated intermittently until the call is answered.

When the receiver at the paystation P is removed to answer the call, a direct current circuit is closed for relay 52 including the bridge at the paystation, whereupon relay 52 operates and closes a locking circuit for itself at armature 59, at the same time connecting ground potential to the lower terminal of the upper winding of relay 53. At armatures 58 and 60 and their working contacts, the talking circuit is completed and at the same time a circuit for the reversing relay 53 is completed. Relay 53 operates and reverses the connections of relay 54 to the trunk conductors, thereby causing a reversal of current in the upper winding of the polarized relay 223. This causes relay 223 to operate and close the circuit of relay 222. Re-

lay 222 operates, shunting armature 226 at armature 229, shunting armature 227 at armature 230, and at armature 228 opening the circuit including impulsing relay 221 and supervisory relay 263 at the main toll board at its resting contact and closing the circuit of impedance control relay 224 at its working contact. Relay 224 operates and closes a locking circuit for itself at armature 234, prepares a circuit for controlling the disconnected signal, as will be described later, at armature 233, and at armatures 232 and 235 opens the short-circuits around the windings of the impedance 225. Relay 221 deenergizes, but since its armatures 226 and 227 are shunted, the release of relay 221 produces no effect. Relay 263 at the toll board, in restoring, opens the circuit of the supervisory lamp L¹, thereby causing the lamp L¹ to be extinguished, which notifies the toll operator that the called subscriber has answered.

The two subscribers may now hold conversation, the talking circuit extending from the exchange C over the trunk conductors 2 and 3, conductors 12 and 13 via the repeater R, through the lineswitch LS', conductors 22 and 23, through the repeating coil R², conductors 22² and 23², through the repeating coil R³, conductor 22' and 23', through the incoming selector S', conductors 42 and 43, through the ringing trunk circuit RTC, line conductors 6 and 7 to the paystation P. The toll operator also has supervision of a connection over the trunk line comprising conductors 252 and 253 which are now connected via the winding of impedance 225 to the conductors 22² and 23². The inclusion of the windings of the impedance 225 in the circuit extending to the main toll board, prevents all but a very small amount of talking current from being shunted thereover, at the same time making it possible for the toll operator to listen to the conversation.

At the termination of the conversation, both subscribers will replace their receivers. When the calling subscriber replaces his receiver (assuming he is first to replace his receiver), the switches in the exchange C associated with the connection are released and the bridge across the trunk conductors 2 and 3 is opened. The opening of the bridge across the line conductors 2 and 3 opens the circuit of the line relay 204 in the trunk relay group TRG. Relay 204 thereupon deenergizes and opens the circuit of relay 201 at armature 212, and opens the circuit of relays 202 and 203 at armature 213. Relays 201 and 202 deenergize immediately and relay 203, being slow acting, deenergizes a short time thereafter. Due to the slow acting characteristic of relay 203, battery through resistance 205 is again momentarily connected to conductor 255 but this has no utility in this particular type of connection. With relays 201 to 204, inclusive, in a deenergized con-

dition, ground potential is again applied to conductor 255 by way of armature 213 and the resting contact, working contact and armature 233, through the winding of relay 221, resting contact and armature 211, therefore again closing the circuit of relay 263 at the main toll board in series with relay 221. Relay 263, in operating, again closes the circuit of lamp L' . The lighting of lamp L' at this time indicates to the operator that the conversation has terminated and that one of the subscribers has hung up his receiver.

When the called subscriber replaces his receiver, the bridge across the line conductors 6 and 7 is opened, thereby causing the deenergization of reversing relay 53. Relay 53 in releasing its armatures again causes the current flow over the trunk conductors 42 and 43 connected to conductors 22' and 23' to be reversed back to normal, thereby causing the polarized relay 223 to restore its armature 231 to normal. The restoration of armature 231 opens the circuit of relay 222 which likewise restores its armatures to normal.

In response to the lighting of lamp L' , the operator removes the plug of the cord circuit used from the jack J , thereby opening the circuit of the sleeve relay 264, and also the locking circuit of relay 262. Relays 262 and 264 restore their armatures to normal, and in so doing disconnect the supervisory relay 263 from conductor 257, again connecting ground through the lower winding of relay 265 thereto. As a result, relay 263 deenergizes and opens the circuit of lamp L' . At the exchange A, the line relay 221 also deenergizes and opens the bridge across the conductors 22' and 23' at armature 227, and also opens a point in the talking circuit at armature 226. Opening the bridge across conductors 22' and 23' opens a circuit of line relay 54 in the ringing trunk circuit RTC. Relay 54 deenergizes, and opens the circuit of relay 51 at armature 61. Relay 51 deenergizes and at armatures 55 and 57 again connects the line conductors 6 and 7 to the lineswitch LS^2 , and at armature 56 disconnects ground potential from the release conductor 44 and release conductors 18, 24', 24, 14, and 34 serially connected thereto with the following results: lineswitch LS^2 again places the normal ground and battery connections to conductors 16 and 17; the selector S' restores to normal in the usual manner; the energizing circuit of relay 224 as well as the polarizing circuit of relay 223 in the trunk relay groups TRG is opened, relay 224 restoring its armatures to normal; and the various trunk branches used in the connection are again marked idle.

Should the called subscriber be the first to replace his receiver, the same operations would result, except that the operations resulting from the replacement of the receiver at the called paystation would then precede

those resulting from the replacement of the receiver at the calling station. In such a case the relay 263 at the main toll board would be energized to give the disconnect signal as soon as the called subscriber replaces his receiver from ground placed on conductor 255 by way of armature 228 and the resting contact, rather than by way of armature 213 and its resting contact and working contact and armature 233, as is the case when the calling subscriber replaces his receiver first. Thus it is seen that the toll operator receives the disconnect signal as soon as either one of the subscribers replaces his receiver.

From the description of the foregoing connection, it is readily apparent that any one of the subscribers in the exchange A can also establish a connection to the paystation P. For instance, should the subscriber at substation A' wish to establish a connection with the paystation P, he likewise removes his receiver and dials the long distance number, resulting in the extension of a connection to the toll operator by way of the lineswitch LS and a local selector, such as selector S, and the outgoing branch of a trunk line extending to the toll board such as the one comprising conductors 252 and 253 the outgoing branch of which is also accessible in the banks of the local selectors. All operations concerning such a connection are identical to those described above.

It is also evident that a calling party at the paystation P can also obtain connection with any of the local subscribers in the exchange A, or any of the subscribers in the exchange B in a similar manner. To establish such a connection, the subscriber at the paystation P merely removes his receiver which causes a connection to be extended to the main toll board via the line switch LS^2 an outgoing branch of one of the trunks extending to the main toll board, such as the one comprising conductors 252 and 253, as previously described. After learning the name or number of the wanted subscriber, the toll operator then sets up the connection by way of a selector such as selector S' , and a connector such as connector C, if the call is for a subscriber in exchange A, or by way of one of the branches of one of the trunk lines extending to exchange C such as the branch comprising conductors 32, 33, and 34, connected to conductors 2 and 3 via the repeater R. The repeater R repeats the impulses dialed by the toll operator to the automatic exchange C to control the setting up connection to the wanted subscriber in that exchange.

Should a party at the paystation P, or any subscriber at exchange A or exchange B, wish to obtain a connection with some one outside of the system or some one in the system not served by either exchange A or exchange B, the call also extended to the toll operator in

the same way as indicated above, and the toll operator further extends the connection by inserting the opposite end of a cord used to answer the calling party in the jack of a trunk leading to the exchange serving the called party.

In the establishment of such a connection the operation of relays 201 to 204, inclusive, of a trunk relay group TRG is identical to that previously described. However, it is obvious, that none of the relays 221 to 224 come into play (assuming that the call is extended over the trunk comprising conductors 252 and 253). In this case the talking circuit extends over the conductors 22 and 23, through repeating coil R^2 , conductors 22² and 23², armatures 232 and 235 and their resting contacts, through repeating coil R^4 , over the trunk conductors 252 and 253, through repeating coil R^5 , tip and ring of jack J, and through the cord circuit used to the exchange serving the calling subscriber.

In this type of connection, the operations for giving the toll operator the disconnect signal in response to the replacement of the receiver by the calling subscriber are somewhat different than those previously described. When the calling subscriber replaces his receiver at the termination of the call, as in the previously described connections, relay 204 deenergizes and opens the circuit of relays 201, 202, and 203, and due to the slow-acting characteristic of relay 203, battery through resistance 205 is connected to conductor 255 during the time that relay 203 holds up its armatures after relay 201 has released its armatures. This operation had no utility in the previously described connections, but in this case, causes the momentary energization of relay 261 at the main toll board, noting that in the establishment of this type of connection neither relay 262 nor relay 263 is operated since the dial D is not used and key K is not operated. Relay 261 operates responsive to this momentary energization and closes the locking circuit for itself at armature 267, and at armature 266 closes a circuit for the supervisory lamp L'. The lighting of the lamp L' indicates to the toll operator that the calling subscriber has replaced his receiver. The other operations concerning the release of the apparatus used are similar to those previously described.

Toll connections to any of the subscribers in the exchange A or exchange C or to the paystation P from distant points or from subscribers served by one of the other exchanges in the system may also be established. To establish such a call, the connection is first extended to the toll operator from the distant point or the calling substation in any well known manner. The toll operator, after learning the name or number of the wanted subscriber, which it will be assumed is a subscriber in the exchange C, for example, in-

serts the calling end of the cord used to answer the call into the jack of an idle trunk extending to exchange B, for example jack J. She then operates the dial key K and dials the number of the wanted subscriber. The operations following are an identical to those previously described, except that no circuit is closed for relay 224 when relay 222 is operated after the called party answers, since relay 201, as well as relays 202, 203 and 204, is not operated. The talking connection in this case extends over trunk conductors 252 and 253, through repeating coil R^4 through repeating coil R^5 , over conductors 22' and 23' through the selector S' to the exchange C and the called subscriber by way of a trunk such as the one comprising conductors 2 and 3.

This completes the description of the operation of the invention. What is considered new and is desired to have protected by Letters Patent will be pointed out in the appended claims.

What is claimed is:

1. In a telephone system, a first and a second exchange, a trunk line connecting said exchanges, a calling and a called line, means at the first exchange for establishing a connection from said calling line to said second exchange over said trunk line, means at said first exchange controlled over said trunk line for establishing a connection from said calling line to said called line, a signal at said second exchange, and means controlled by either party when he replaces his receiver for operating said signal.

2. In a telephone system, a first and a second exchange, a trunk line connecting said exchanges, a calling and a called line, means at the first exchange for establishing a connection from said calling line to said second exchange over said trunk line, means at said first exchange controlled over said trunk line for establishing a connection from said calling line to said called line, a signal at said second exchange, and means controlled by the called party when he removes his receiver and by either party when he replaces his receiver for operating said signal.

3. In a telephone system, a first and a second exchange connected by a trunk line, a calling line in said first exchange, means for establishing a connection from said calling line to said second exchange over said trunk line, a signal at said second exchange, means at said first exchange for momentarily applying a certain potential to a conductor of said trunk line responsive to the extension of said connection to operate said signal, a called line, and means at said first exchange controlled from said second exchange over said conductor for establishing a talking connection from said calling line to said called line.

4. In a telephone system, a first and a second exchange connected by a trunk line, a calling line in said first exchange, means for

establishing a connection from said calling line to said second exchange over said trunk line, a signal at said second exchange, means at said first exchange for momentarily applying a certain potential to a conductor of said trunk line responsive to the extension of said connection to operate said signal, a called line, and means at said first exchange controlled from said second exchange over said conductor for establishing a talking connection from said calling line to said called line while the first connection is intact.

5. In a telephone system, a first and a second exchange connected by a trunk line, a calling line in said first exchange, means for establishing a connection from said calling line to said second exchange over said trunk line, a signal at said second exchange, means at said first exchange for operating said signal over a conductor of said trunk line responsive to the extension of said connection, a called line, means at said first exchange controlled over said conductor for establishing a talking connection from said calling line to said called line, a second signal at said second exchange individual to said trunk line, and means controlled by the called party over said conductor when he removes his receiver to answer the call for operating said second signal.

6. In a telephone system, a first and a second exchange connected by a trunk line, a calling line in said first exchange, means for establishing a connection from said calling line to said second exchange over said trunk line, a signal at said second exchange, means at said first exchange for operating said signal over a conductor of said trunk line responsive to the extension of said connection, a called line, and means at said first exchange controlled from said second exchange over said conductor for establishing a talking connection from said calling line to said called line, a second signal at said second exchange, and means controlled by either party over said conductor when he replaces his receiver at the termination of the call for operating said signal.

7. In a telephone system, a trunk line terminating at one end at an operator's position and having two branches at the other end, a calling and a called line, means controlled by the calling party for extending a connection to said operator's position over one branch, means responsive to said connection for momentarily connecting a source of potential to one conductor of said trunk to signal the operator, and means controlled by the operator over said conductor for establishing a connection between said calling and called line via said branches in series.

8. In a telephone system, a trunk line terminating at an operator's position, a calling and a called line, means for connecting said calling line to said trunk line, a battery,

means responsive to said connection for momentarily connecting one pole of said battery to a conductor of said trunk line to signal the operator, and means controlled by the operator over said conductor for establishing a connection between said calling and called lines.

9. In a telephone system, a trunk line terminating at an operator's position, a calling and a called line, means for connecting said calling line to said trunk line, a battery, means responsive to said connection for momentarily connecting one pole of said battery to a conductor of said trunk line to signal the operator, means controlled by the operator over said conductor for establishing a connection between said calling and called lines, and means responsive to the replacement of the receiver on one of the lines for connecting the other pole of said battery to said conductor to give the operator the disconnect signal.

10. In a telephone system, a trunk line terminating at an operator's position, a calling and a called line, means for connecting said calling line to said trunk line, means responsive to said connection for momentarily connecting a characteristic potential to a conductor of said trunk line to signal the operator, means controlled by the operator for extending the connection to the called line, and means responsive to the replacement of the receiver on the calling line for again momentarily connecting said characteristic potential to said conductor to give the operator the disconnect signal.

11. In a telephone system, a trunk line extending from an exchange to an operator's position and having the same potential applied to both ends of a conductor of said trunk line, a calling line at said exchange and means for connecting it with said trunk line, means responsive to establishment of said connection for momentarily applying a different potential to said conductor at the exchange to signal the operator at said position, a called line, an automatic switch connected to said trunk line at the exchange, and means controlled by the operator for intermittently applying a different potential to said conductor to control the operation of said switch to connect with said called line.

12. In a telephone system, a trunk line, extending from an exchange to an operator's position and having the same potential applied to both ends of a conductor of said trunk line, a calling line at said exchange and means for connecting it with said trunk line, means responsive to establishment of said connection for momentarily applying a different potential to said conductor at the exchange to signal the operator at said position, a called line, an automatic switch connected to said trunk line at the exchange, means controlled by the operator for inter-

- mittently applying a different potential to said conductor to control the operation of said switch to connect with said called line, and means operative when the called party answers the call for disconnecting the first potential from said conductor at the exchange to signal the operator.
13. In a telephone system, a trunk line, extending from an exchange to an operator's position and having the same potential applied to both ends of a conductor of said trunk line, a calling line at said exchange and means for connecting it with said trunk line, means responsive to establishment of said connection for momentarily applying a different potential to said conductor at the exchange to signal the operator at said position, a called line, an automatic switch connected to said trunk line at the exchange, means controlled by the operator for intermittently applying a different potential to said conductor to control the operation of said switch to connect with said called line, means operative when the called party answers the call for disconnecting the first potential from said conductor at the exchange to signal the operator and for reapplying said first potential to said conductor when either party replaces his receiver at the end of the call to give the operator the disconnect signal.
14. In a telephone system, a first exchange, a first and a second switch at said exchange, a second exchange, a two-way trunk extending from said first exchange to said second exchange, an outgoing branch for said trunk accessible to said first switch, an incoming branch for said trunk terminating in said second switch, a third switch at said first exchange also having access to said outgoing branches, a third exchange, a second two-way trunk line extending from said third exchange to said first exchange and terminating thereat in said third switch and being accessible to said second switch, and subscribers' lines at said first exchange having access to said first switch and being accessible to both said first switch and said second switch.
15. In a telephone system, an exchange, two lines terminating at said exchange, an operator's switchboard, a trunk line extending from said switchboard to said exchange, means controlled over said trunk line for connecting said lines to establish a talking connection, and a signal at said switchboard responsive to the replacement of the receiver by the first party to hang up at the termination of the conversation.
16. In a telephone system, an exchange, two lines terminating at said exchange, an operator's switchboard, a trunk extending from said exchange to said switchboard, means for establishing a connection from the first line to said trunk, a signal at said switchboard, means for controlling said signal over one conductor of said trunk independent of the other conductor to notify the operator of said connection, and means controlled from said switchboard over said one conductor independent of the other for establishing a connection from the first line to the second line.
17. In a telephone system, an exchange, an operator's switchboard, a trunk extending from the exchange to the switchboard, a battery at the exchange having one pole grounded, a second battery at the switchboard having one pole grounded, an impulsing relay at the exchange connected to the grounded pole of the first battery and to a conductor of said trunk, a call relay at said switchboard connected to the grounded pole of the second battery and to said conductor, means at the exchange for momentarily connecting the ungrounded pole of the first battery to said conductor to operate said call relay, and means at said switchboard for intermittently connecting the ungrounded pole of the second battery to said conductor to operate said impulsing relay.
18. In a telephone system, an exchange, an operator's switchboard, a trunk extending from the exchange to the switchboard, a battery at the exchange having one pole grounded, a second battery at the switchboard having one pole grounded, an impulsing relay at the exchange connected to the grounded pole of the first battery and to a conductor of said trunk, a call relay at said switchboard connected to the grounded pole of the second battery and to said conductor, means at the exchange for momentarily connecting the ungrounded pole of the first battery to said conductor to operate said call relay, means at said switchboard for intermittently connecting the ungrounded pole of the second battery to said impulsing relay, an automatic switch at said exchange for extending a call controlled by said impulsing relay, an answering relay at said switchboard connected to the ungrounded pole of said second battery, means for connecting said answering relay to said conductor after said switch is operated to cause said answering relay to energize in series with said impulsing relay, and means for disconnecting the ungrounded pole of the first battery from said impulsing relay when the call is answered to cause said answering relay to deenergize.
19. In a telephone system, a first exchange, a second exchange, a third exchange, a non-numerical hunting switch and a numerical selector switch in said second exchange, a two-way trunk line extending from said first exchange and terminating at said second exchange in said hunting switch and accessible to said selector switch, and a two-way trunk line extending from said third ex-

- change and terminating at said second exchange in said selector switch and accessible to said hunting switch.
20. In a telephone system, a first exchange, a second exchange, a third exchange, a non-numerical hunting switch and a numerical selector switch in said second exchange, a two-way trunk line extending from said first exchange and terminating at said second exchange in said hunting switch and accessible to said selector switch, a two-way trunk line extending from said third exchange and terminating at said second exchange in said selector switch and accessible to said hunting switch, a local selector switch having access to said second trunk line, and a connector also accessible to said local selector switch and to said first selector switch.
21. In a telephone system, an exchange, an operator's switchboard, two-way trunk lines extending between the exchange and the switchboard, each having an incoming and an outgoing branch at said exchange, numerical selector switches terminating the incoming branches, a non-numerical switch at said exchange having access to said outgoing branches, and a paystation line terminating at said exchange and having a calling branch terminating in said non-numerical switch and having a called branch directly accessible to said selector switches.
22. In a telephone system, an exchange, an operator's switchboard, two-way trunk lines extending between the exchange and the switchboard, each having an incoming and an outgoing branch at said exchange, numerical selector switches terminating the incoming branches, a non-numerical switch at said exchange, having access to said outgoing branches, a paystation line terminating at said exchange and having a calling branch terminating in said non-numerical switch and having a called branch directly accessible to said selector switches, and means individual to said called branch for signalling over said paystation line when a call is extended thereto and for interrupting the signalling when the party thereat answers.
23. In a telephone system, a trunk line connecting two exchanges and having two branches at one of the exchanges, means controlled over the trunk line for connecting said two branches to two lines, respectively to complete a talking connection excluding the undivided portion of said trunk line, an impedance coil, and means for inserting said coil in the undivided portion of said trunk line to reduce the shunting effect of a bridge at the distant end of said trunk line.
24. In a telephone system, a calling line and a called line, a trunk line having two branches, means for completing a talking connection between said calling line and said called line over said two branches excluding the undivided portion of said trunk line, an impedance coil, and means responsive to the called subscriber removing his receiver for inserting said coil in the undivided portion of said trunk line to reduce the shunting effect of a bridge in the undivided portion of said trunk line.
25. In a telephone system, a first exchange, a second exchange, a calling and a called line, a trunk line connecting said exchanges and having two branches at said first exchange, means at said first exchange for establishing a connection from said calling line to said second exchange over one branch of said trunk line, means at said first exchange controlled over said trunk line for connecting the other branch of said trunk line to said called line, means at said first exchange for completing a talking connection between said calling line and said called line over said two branches excluding the undivided portion of said trunk line, an impedance coil, and means for inserting said coil in the undivided portion of said trunk line to reduce the shunting effect of a bridge in said trunk line at said second exchange.
26. In a telephone system, an exchange, two lines terminating at said exchange, an operator's switchboard, a trunk line extending from said switchboard to said exchange and having two branches in said exchange, means controlled over said trunk line for connecting said lines to the two branches of said trunk line to establish a talking connection over said branches excluding the undivided portion of said trunk line, an impedance coil, and means for inserting said coil in the undivided portion of said trunk line to reduce the shunting effect of a bridge in said trunk line at said operator's switchboard.
27. In a telephone system, a first exchange, a second exchange, a calling and a called line, a trunk line connecting said exchanges and having two branches at said first exchange, subscriber controlled means at said first exchange for connecting said calling line to said second exchange over one branch of said trunk line, means at said first exchange controlled over said trunk line for connecting the other branch of said trunk line to said called line, a signal individual to said trunk line at said second exchange, means responsive to the called subscriber removing his receiver for controlling said signal over a conductor of said trunk line, and means at said first exchange for completing a talking connection over the two branches of said trunk line excluding the undivided portion of said trunk line.
- In witness whereof, I hereunto subscribe my name this 7th day of March, A. D. 1927.
- CLARENCE E. LOMAX.
